CHINESE CHESS BOARD

John Tchou, 127 Setauket Trail,
Medford Lakes, N.J. 08055

Filed Mar. 21, 1973, Ser. No. 343,265

Term of patent 14 years

Int. Cl. D21—01

U.S. Cl. D34—5 SS

The sole figure is a plan view of a chinese chess board, showing my new design.

The board is of conventional thickness.

I claim:

The ornamental design for a chinese chess board, as shown and described.
